VANITY CASE

Jacob Aronstein, New York, N. Y.

Application October 27, 1937, Serial No. 171,191

5 Claims. (Cl. 132—79)

This invention relates to a vanity case, and more especially to such a device comprising a means for dispensing perfume in severable combination with other toilet accessories. The invention is more especially useful in vanity cases adapted to be carried in handbags or pockets.

An object of the invention is to provide a means of carrying a suitable supply of perfume for relatively long periods of time without evaporation or loss while providing a ready means of dispensing or applying said perfume to the human body.

Another object of the invention is to combine such perfume dispenser with other toilet accessories, such as powder and a mirror, in an attractive compact and readily accessible manner.

The invention consists in the novel structure, arrangement and cooperative relationship of the parts embodied by way of example in the apparatus hereinafter described as illustrating the present preferred form of the invention, and the invention will be more particularly pointed out in the appended claims.

Further objects and advantages of the invention will more fully appear from the following description taken in connection with the accompanying drawing, which shows, by way of example, the preferred embodiment of the invention.

Referring to the drawing, in which the same reference characters indicate the same parts in the various views:

Fig. 1 is a perspective view of the vanity case with the cover opened.

Fig. 2 is a perspective view of the perfume dispensing unit showing it entirely removed from the vanity case.

Fig. 3 is a plan view of the device illustrated in Fig. 1 with the cover closed, and

Fig. 4 is a transverse cross-sectional view taken at 4—4 of Fig. 3.

Referring to the drawing, and more particularly to Fig. 1: the body of the case is indicated as 1 and the cover 2 is hingedly secured thereto at 3. The body 1 is provided with a suitable catch 4 adapted for cooperative engagement with a recess 5 formed in the cover and serving to releasably hold the cover in closed position. The cover 2 carries secured to the interior thereof adjacent the forward end a mirror 6 which, together with its retaining frame, is offset inwardly somewhat from the cover panel. The body is provided adjacent its forward end with a compartment for containing powder, and this compartment has a closure or cover 7 hingedly secured to the body and a suitable latch 8 for

releasably holding it in closed position; the cover being depressed as at 9 to accommodate the offset mirror 6 and its frame. Toward the rear of the body a recess 10 is provided for accommodating the perfume dispenser illustrated in Fig. 2 and which will now be more particularly described.

The perfume dispenser unit illustrated in Fig. 2 comprises an upper portion 11 and a lower portion 12; the upper portion being provided with an engageable portion or handle 13 serving as a means for grasping the upper portion in order to remove it from the lower portion when it is desired to apply the perfume, and the lower portion is provided with a flange 14. The upper and lower portions have an interfitting engagement serving to provide a unitary receptacle for preventing evaporation of the volatile ingredient such as perfume. Referring to Fig. 4, it will be seen that the upper portion 11 in the present embodiment comprises an inner shell 15 which serves to hold in position within the upper portion a wad of highly absorbent material 16 which in the preferred embodiment is a fine grained sponge of disc formation which I have found to be ideally suited for this purpose. The inner shell 15 is provided with a lower inwardly extending lip 17 which extends only a slight distance inwardly to leave an extensive lower surface 18 of the sponge positioned adjacent the lower end of the upper portion 11, the sponge bulging somewhat downwardly interiorly of the said flange so as to come into contact with the human body for purposes of contact application of the perfume carried in the sponge. As will be seen from Fig. 4, the lower side wall of the body 15 of the upper portion 11 is in tight interfitting telescopic engagement with the interior of the lower portion 12, and this engagement is such as to provide a seal sufficient to prevent substantial evaporation of the perfume. In effect, the upper portion 11 thereby provides a receptacle for the perfume carried in the sponge, and the lower portion 12 provides a closure or cover for said receptacle. The lower portion 12 has a snug fit within the recess 10 and the frictional contact with the walls of said recess tends to hold the lower portion 12 seated therein when it is merely desired to remove the portion 11 therefrom. The flange 14 of the portion 12 rests upon the cooperating shoulder of the body 1 but is knurled so as to permit removal of the portion 12 when desired.

The cover 2 is provided with an opening 19 in register with the portion 12 of the perfume dis-

pensing unit and is of such size as to permit the upper end thereof to project therethrough and the entire upper portion 11 to be removed therethrough when the cover is closed (Fig. 3). The 5 marginal edge of the hole 19 overlies the flange 14, however, and serves as a positive means of preventing the withdrawal of the portion 12 when the cover is closed.

From the foregoing it will be understood that 10 when the user desires merely to apply perfume, with the cover closed as illustrated in Fig. 1, the handle 13 is grasped and by a slight twist and pulling motion the receptacle portion 11 is withdrawn from the case and the lower surface of the sponge 16 is touched to that part of the body 15 where it is desired to apply the perfume. By raising the cover 2 and grasping the flange 14 the unitary perfume dispenser may be removed in its entirety and placed in the pocket or handbag for separate use if desired. The perfume 20 dispenser unit thus provided serves to store the desired amount of perfume in a condition where it may not be spilled, even when the unit is opened, and the container is sealed to an extent which prevents substantial evaporation of the 25 volatile perfume when not in use; it having been demonstrated that perfume impregnating the sponge will remain in condition for use for several months.

Having thus described my invention with particularity with reference to the preferred embodiment of the same, it will be obvious to those skilled in the art after understanding my invention, that other changes and modifications may be made therein without departing from the spirit and scope of the invention, and I aim in the appended claims to cover such changes and modifications as are within the scope of the invention.

What I claim is:

1. In a pocket vanity case, the combination of a case comprising a body and a cover, a perfume dispenser removably seated in said case, said dispenser comprising a receptacle open at one end and closed at the other and containing a wad 40 of highly absorbent material for holding a volatile liquid, said wad having an exposed surface contiguous said open end for contact application by the user, said dispenser receptacle being disposed in telescopic sealed engagement within a cooperating closure member held in said case with the closed end of the receptacle facing outwardly, whereby the receptacle serves to enclose said wad within said cooperating closure member and to prevent substantial evaporation of said volatile 45 ingredient therefrom.
2. In a pocket vanity case, the combination of a case comprising a body and a cover, a perfume dispenser removably seated in said case body, said dispenser comprising a receptacle open at one end and closed at the other and containing a wad 50 of highly absorbent material for holding a volatile liquid, said wad having an exposed surface contiguous said open end for contact application by the user, said dispenser being disposed in sealed

engagement within a recess provided in said body with the closed end of the receptacle facing outwardly, whereby the receptacle serves to enclose said wad within said recess and to prevent substantial evaporation of said volatile ingredient 5 therefrom, said dispenser receptacle being provided with an engageable portion for the removal thereof from said body recess and said case cover having an opening in register with said receptacle through which opening said receptacle may be 10 engaged and said dispenser removed from said body recess while said cover is closed.

3. In a device of the character described, the combination of a case comprising a body and a cover, a unitary perfume dispenser removably seated in said case, said dispenser comprising a receptacle having an end wall and side walls containing a wad of highly absorbent material secured therein for holding a volatile liquid, said wad having an exposed surface contiguous an 20 open end for contact application by the user and a closure in sealed interfitting engagement with the side walls of said receptacle for preventing substantial evaporation of said liquid, the dispenser closure being removably seated in a recess in the body of said case with the receptacle in register with and removable through a hole in the cover of said case, and means jointly provided by said receptacle closure and body cover for preventing the withdrawal of said dispenser unit 25 when the cover is closed while permitting removal of said unit when the cover is open.

4. A combination vanity case comprising a body and a cover therefor, said body having a compartment for powder and a closure therefor and a recess for accommodating a perfume dispenser, a perfume dispenser having a lower portion removably seated in said body and an interfitting upper portion forming a seal with said lower portion and extending through an opening in 40 said body cover, and perfume retaining and dispensing means held within said upper portion, said body cover contiguous said opening overlying a part of the lower portion of said dispenser to prevent its withdrawal when the body cover is 45 closed while permitting the removal through said opening of said upper dispenser portion.

5. In a pocket vanity case, the combination of a body provided with a compartment having a downwardly recessed closure means interconnected to said body and a recess adjacent thereto, a perfume dispenser removably positioned in said body recess and comprising an inverted receptacle containing a wad of highly absorbent material, said receptacle being in sealed engagement within 50 said recess with the closed end facing outwardly, a cover for said body, said cover having an opening in register with said receptacle and through which said receptacle may be removed, and a mirror attached on the inside of said cover in 55 position to be seated within said recessed closure means for said compartment.

JACOB ARONSTEIN.
